P. H. HAMILTON.

PRESSURE ACTUATED MECHANISM FOR OPERATING VALVES OR THE LIKE.

APPLICATION FILED FEB. 17, 1919.

1,362,991.

Patented Dec. 21, 1920.

UNITED STATES PATENT OFFICE.

PAUL H. HAMILTON, OF CLEVELAND, OHIO.

PRESSURE-ACTUATED MECHANISM FOR OPERATING VALVES OR THE LIKE.

1,362,991.

Specification of Letters Patent. Patented Dec. 21, 1920.

Application filed February 17, 1919. Serial No. 277,554.

To all whom it may concern:

Be it known that I, PAUL H. HAMILTON, a citizen of the United States, residing at Cleveland, in the county of Cuyahoga and 5 State of Ohio, have invented a certain new and useful Improvement in Pressure-Actuated Mechanism for Operating Valves or the like, of which the following is a full, clear, and exact description, reference being had 10 to the accompanying drawings.

This invention relates to an improved pressure-actuated device for operating valve or other mechanisms, the same being especially suitable for use in connection with so-called 15 instantaneous water heaters for controlling the gas valves thereof so that when water is drawn from the system, which naturally causes an inflow of a fresh supply to the heater, it will actuate the device and cause 20 it to open the gas valve to supply gas to the burner in proportion to the amount of water flowing through the device; that is, in sufficient amount to heat such a quantity 25 of water during its passage through the circulating element; and the invention in one of its phases, pertains to the combination of a pressure actuated device and a valve operated thereby.

The objects of the invention are to provide 30 a comparatively simple and accordingly cheap device of the above character that is positive of operation under all degrees of pressure; is not likely to get out of order; and wherein the working parts are easily 35 accessible, for purposes of inspection and cleaning, and without the need of disturbing the elements of the system wherewith the device is used.

A further object is to provide a pressure 40 actuated device and fuel supply valve, together with a support which serves to hold the device and valve in proper relation to each other, and which elements constitute a unit for incorporation in instantaneous 45 water heaters that will supply fuel to the burner in direct proportion to the quantity of water flowing through the circulating coil or element; and a further object is to construct such a unit so that the individual parts 50 thereof may be readily withdrawn from the assembly without dismantling the whole.

The foregoing objects, and others which will become apparent as this description proceeds, are attained in the construction illustrated in the accompanying drawing which

constitutes a part hereof and wherein Figure 1 is a more or less diagrammatic representation of a water heater and a system including the same, and showing an installation of my improved pressure-actuated, 60 valve-operating device; Fig. 2 is a sectional detail through the unit comprising the pressure actuated device, fuel valve, and the supporting element by which they are united; and Figs. 3 and 4 are perspective views, re- 65 spectively, of the piston and cylinder or guide, within which the piston operates, of the pressure actuated device.

While I do not restrict the use of my invention to the controlling of fuel valves of 70 instantaneous water heaters, the same is peculiarly adapted to such use, as I have already stated and for that reason I have shown it in such environment in the present illustration.

In the drawing, 1 represents the water circulating coil or element and 2 a gas burner situated a suitable distance therebelow, and both are inclosed within a casing comprising a shell 3, top 4, and base ring 5. Water is 80 admitted from a supply pipe 8, through the pressure actuated device 10 and connection 11, to the coil 1, and it is drawn off through a pipe 12 which has applied to it a faucet 13.

The burner 2 is supplied with gas from a 85 pipe 15 through a controlling valve 16, the usual pilot 17 cutting into the supply pipe ahead of valve 16.

Referring particularly to the sectional view of Fig. 2, the pressure actuated device 90 10 consists of a cylindrical casing that is divided longitudinally into what I shall term a supply chamber 20 and an outlet chamber 21 by an internal, circumferential seat 22, and parts coöperating therewith and which 95 I shall presently describe.

The supply pipe 8 has connection, through a union 23, with the inlet extension 24 of the supply chamber; and the previously mentioned connection 11, which leads to the 100 circulating coil of the heater, communicates with the outlet chamber 21 through the hollow boss 25 of the casing.

The outer or open end of the casing is internally threaded to receive the threaded 105 portion 27 of a cylindrical guide 28 that is designed to be tightly screwed into place by the application of a wrench or other suitable tool, to the wrench receiving portion 30 thereof. The inner end of the guide is 110

made to accurately fit the circumferential seat 22, thus effectually separating the chambers 20 and 21 except as communication may be had through openings 31 of the guide 5 which occur between its threaded portion 27 and its extreme inner end. To prevent any foreign substance which may enter chamber 20 from passing further, I cover the openings 31 with a suitable screen designated 32.

10 A piston 35, comprising a cylindrical wall 36 and a circular end wall 37, is reciprocable within the guide 28. The cylindrical wall 36 has a triangular port 38, the apex whereof 15 is disposed toward the inner or closed end of the piston. Short pins 39 which project outwardly from the face of the wall 36 are located on opposite sides of the port 38, restrict the piston against undue angular 20 movement by contacting with the end walls of the particular opening 31 wherewith the port 38 registers, and against undue longitudinal movement by engaging the inner wall of said opening.

25 A rod 40 is secured, as by nuts 41, to the circular wall 37 of the piston and the same extends outward through an aperture in the end wall of the casing and through an extension 43 thereof which serves as the 30 basic element of a stuffing box 45. The stuffing box comprises a gland nut 46 that is threaded onto the extension and operates to force a follower 47 inwardly to compress the packing material 48 all of which is in 35 accordance with the usual practice. A spring 49, interposed between the end wall of the piston 35 and the opposed wall of the casing tends to retain the piston in normal position.

40 A bracket 50 is attached to and depends from the base ring 5 of the heater and the apertured end of one branch 51 thereof is applied to the extension 43 of device 10 and is firmly clamped against a shoulder 52 by a 45 nut 53 that is screwed onto the threaded extension ahead of the gland nut 46.

45 In identical manner, the casing of valve 16 is attached to the branch 55 of the bracket. A rod 58 extends through the 50 stuffing box of the valve casing and has connection at its inner end with the valve disk 60 that is arranged to coöperate with a seat 61. A spring 62, interposed between the valve disk and the opposed end wall of a cap 55 63 that is threaded into the side of the valve 68 casing and is therefore adjustable to vary the tension of the spring, tends to hold the valve disk to its seat. It will be observed that, with the parts assembled as above 60 stated, the rods 40 and 58 will be in alignment.

65 Under normal conditions, with the system closed, uniform pressure prevails on both sides of the piston 35 within the supply and outlet chambers 20 and 21, but as soon as

there is a draft upon the system, as when the faucet 13 is opened, the pressure falls immediately within the system, and consequently within the outlet chamber 21, permitting the higher pressure prevailing within the supply chamber 20 and communicated through port 38 to the interior of the piston, to force the piston toward the left (as the parts are viewed in Fig. 2) against the action of the spring 49. The movement of the 70 piston in this direction will, through rods 40 and 58, open the valve 60 and allow the passage of gas to the burner 2 which is ignited by the pilot 17 to heat the water now flowing through the coil or circulating element. The 80 piston will move only far enough to uncover and thus open port 38 sufficiently to replenish the system with a quantity of water equal to that drawn off so that the extent of movement of the piston is dependent upon 85 the extent to which the faucet is opened. Likewise, valve 60 will be removed from its seat a distance dependent upon the movement of the piston so that gas is supplied in a quantity proportional to and sufficient 90 to heat the amount of water flowing through the system. Upon reflection it will be seen that the amount of gas flowing through the valve increases approximately in proportion to the extent of movement of the valve 95 disk away from its seat. To provide for the same increase of water supply over the longitudinal movement of the piston 35, the port 38 is made of the shape shown with its smaller end toward the advancing end of the 100 piston.

Attention is called to the fact that, when it is desired to clean the pressure actuated device, or inspect its parts for any purpose, it is only necessary to unscrew the guide 28 from the casing and withdraw it and the piston endwise therefrom. The fact that the guide carries both the screen and piston makes the cleaning operation extremely simple, for with these parts removed they 110 can be easily handled and thoroughly cleansed.

Having thus described my invention, what I claim is:

1. In a device of the character set forth, 115 the combination of an open sided casing having an inlet and outlet, a member insertible through the open side of the casing and having a part arranged to close said open side, and an actuating element carried by said member and removable therewith and adapted to be operated by the passage of fluid through the casing.

2. In a device of the character set forth, 125 the combination of a casing having an opening and provided with an inlet and an outlet, a member insertible through the opening for dividing the casing into a supply chamber and an outlet chamber wherewith the inlet and outlet communicate respectively, 130

5 said member having a part for closing the aforesaid opening, and an actuating element, serving normally as a barrier between said chambers, movably carried by the member and adapted to be shifted by pressure fluid within the supply chamber to permit communication between the chambers.

10 3. In a device of the character set forth, the combination of a casing having an open end and an internal annular seat situated between its ends, the casing having an inlet on one side of said seat and an outlet on the other side thereof, a member insertible through the open end of the casing and having a part for closing the open end and arranged within the casing to engage the aforesaid seat and divide the casing into a supply chamber wherewith the inlet communicates and an outlet chamber having 15 communication with the outlet, said member having an opening through which said chambers may communicate, a screen covering said opening and removable with said member, and a device movably carried by 20 the member and removable therewith and having a passageway, said element being adapted to be shifted by fluid from the supply chamber to a position wherein intercommunication is established between the 25 chambers through its passageway.

30 4. In a device of the character set forth, the combination of a casing having an internally threaded open end and an internal, annular seat disposed between its ends, the 35 casing having an inlet on one side of said seat and an outlet on the other side thereof, a guide member adapted to be threaded into the open end of the casing and having a part for coöperation with the aforesaid seat 40 whereby said member divides the casing into a supply chamber and an outlet chamber wherewith the inlet and outlet communicate respectively, said member having an opening through which said chambers may communicate, a screen covering said opening and carried by and removable with said member, and a hollow, open-ended piston reciprocable within the guide and having a closed end disposed toward the outlet chamber, the side 45 wall of the piston having a port through which communication is established between the supply chamber and its interior and arranged, when the piston is shifted by pressure fluid from the supply chamber, to open 50 into the outlet chamber.

55 5. In a device of the character set forth, the combination of a casing having an internally threaded open end and an internal annular seat between its ends, the casing 60 having an inlet on one side of said seat and an outlet on the other side thereof, a guide member adapted to be threaded into the open end of the casing and having a part for coöperation with the aforesaid seat whereby 65 said member divides the casing into a sup-

ply chamber and an outlet chamber wherewith the inlet and outlet communicate respectively, said member having an opening through which said chambers may communicate, a screen covering said opening and carried by and removable with said member, a hollow, open-ended piston reciprocable within the guide and having a closed end disposed toward the outlet chamber, the side wall of the piston having a port through which communication is established between the supply chamber and its interior and arranged, when the piston is shifted from normal position by pressure fluid from the supply chamber, to open into the outlet chamber, and a spring tending to maintain the piston in normal position.

70 6. An automatic valve unit for instantaneous water heaters organized of a pressure actuated device comprising a casing divided 75 into a supply chamber and an outlet chamber and having an inlet and an outlet communicating respectively with said chambers, a piston reciprocable within said casing and having a passageway diminishing in area 80 toward the outlet chamber and through which intercommunication is established between said chambers when the piston is moved by pressure fluid from the supply chamber, a rod having operative connection 85 with the piston and projecting from the casing; a fuel valve comprising a casing incorporating a seat, a valve member for co-operation with the seat, means tending to seat the valve member, a rod operatively 90 connected to the valve member, and projecting from the casing; and means uniting the pressure actuated device and valve casing with their rods arranged for operative engagement with each other.

95 7. An automatic valve unit for instantaneous water heaters organized of a pressure actuated device comprising a casing divided 100 into a supply chamber and an outlet chamber and having an inlet and an outlet communicating respectively with said chambers, a piston reciprocable within said casing and having a passageway diminishing in area 105 toward the outlet chamber and through which intercommunication is established between said chambers when the piston is moved by pressure fluid from the supply chamber; a fuel valve comprising a casing incorporating a seat, a valve member for co-operation with the seat, means tending to 110 seat the valve member; an element uniting the pressure actuated device and valve casing, and operative connections between the piston and valve member.

115 8. An automatic valve unit for instantaneous water heaters organized of a fuel valve comprising a casing having an open side and a valve seat spaced inward from said open side, the opposite side of the casing having a guide aperture, a valve member 120

130

4
for coöperation with the seat, a rod extending from the valve member through the guide aperture, a plug closing the open side of the casing, a spring interposed between said plug and valve member; a pressure actuated device comprising a casing having an open side and provided with an inlet and an outlet, a guide member insertible through the open side for dividing the casing into a supply chamber and an outlet chamber wherewith the inlet and outlet communicate respectively, a piston reciprocable within said guide member and having a passageway diminishing in area toward the outlet cham-

ber and through which intercommunication 15 is established between the chambers when the piston is moved by pressure fluid from the supply chamber, the side of the casing opposite its open side having an aperture, a rod projecting from the piston through 20 said aperture, and means uniting the fuel valve and the pressure actuated device with their rods arranged for engagement with each other.

In testimony whereof I hereunto affix my 25 signature.

PAUL H. HAMILTON.
